UNITED STATES PATENT OFFICE.

ELMER McBURNEY, OF OAKLAND, CALIFORNIA.

CABINET FOR VEHICLES.

1,239,021.

Specification of Letters Patent.

Patented Sept. 4, 1917.

Application filed December 16, 1916. Serial No. 137,393.

To all whom it may concern:

Be it known that I, ELMER McBURNEY, a citizen of the United States, residing at Oakland, in the county of Alameda and State of California, have invented certain new and useful Improvements in Cabinets for Vehicles, of which the following is a specification.

This invention relates to attachments for 10 motor vehicles, and aims primarily to provide means whereby the carrying and storage capacity of the vehicle may be greatly increased without inconvenience to the occupants of the vehicle, and without detracting from the appearance of the latter.

A further object of the invention is to provide a combined commissary and table, which is capable of being readily attached to and detached from the running board of 20 the vehicle, which affords ample space for the accommodation of cooking and serving utensils and food, and which when converted into a table, affords an efficient buffet.

A further object is to provide a device 25 of this character which shall be of light weight and of maximum storage capacity, and yet which is compact and may be easily carried.

With these objects in view, together with 30 others which will appear as the description proceeds, the invention resides in the novel formation, combination and arrangement of parts, all as will be described more fully hereinafter, illustrated in the drawings, and 35 particularly pointed out in the claims.

In the drawings:—

Figure 1 is a fragmentary side elevation of a conventional form of motor vehicle, illustrating the application of an attachment constructed in accordance with the invention;

Fig. 2 is a view similar to Fig. 1, and illustrating the attachment when extended to provide a table;

Fig. 3 is an enlarged sectional view taken upon line 3—3 of Fig. 2;

Fig. 4 is a top plan view of the buffet when extended to the position shown in Fig. 3; and

Fig. 5 is a transverse section taken through the cabinet when the latter is folded or closed.

Referring now more particularly to the drawings, 6 represents generally the vehicle, and 7 the running board or step therefor.

The attachment for the vehicle includes the cabinet indicated generally at 8, which is rectangular in shape and of a size to fit upon the running board of the vehicle. As shown in the drawings, the cabinet is substantially the same length as the running board and is of equal width therewith, and may be fastened to the running board by straps indicated at 9.

Arranged within the cabinet and preferably coextensive therewith and spaced slightly above the bottom of the same is a partition or floor 10, a compartment 11 being formed between the said floor and the bottom of the cabinet. The outer edge of 65 the partition terminates inwardly from the open end of the box, as illustrated in Figs. 3 and 5. The cabinet may, if desired, be equipped with vertical partitions indicated at 12, to divide said cabinet into separate 70 and distinct storage compartments.

Hinged to the open end of the cabinet is a door or closure 13. This door is hinged in the same horizontal plane as the floor or partition 10, so that when the door is swung to horizontal or open position, the said door will form a substantial continuation of the floor 10. The door is of a size to snugly fit the open end of the cabinet so as to tightly close the same, and may be locked in closed 80 position by application of a lock to the loop 14 which engages through the hasp 15 hingedly connected to the cabinet. To the upper or free edge of the door 13 is hinged 85 secured a leaf 16, the latter being of equal length and width with the door, and to the free or outer edge of the leaf 16 is hinged secured a second leaf 17. The leaf 17 is in a like manner hinged connected with a leaf 18, and the latter is also hinged to an end leaf 19. These leaves are preferably 90 formed of thin material, so that when folded upon each other, they will occupy but little space, and it will be observed, particularly with reference to Fig. 5, that when in closed position, the leaves take up but very little of the space within the cabinet. It will be observed also that the end leaf 19 when the device is in closed position, engages with the outer edge of the floor or partition 10, so that sliding movement of the leaves within the cabinet will be prevented.

When it is desired to provide a table, the door is swung to horizontal position, and the various leaves are swung upon 100 105 110

their hinges in substantially the position shown in Figs. 3 and 4.

The means for supporting the extended leaves in proper horizontal position comprises arms 20. These arms are of a size to permit of their fitting snugly within the compartment 11 beneath the floor 10 of the cabinet, and may, if desired, be hinged at their inner ends within the said compartment. Pins 21 are illustrated in the present instance as pivotally securing the inner extremities of the arms 20 within the housing, and the said extremities are hinged adjacent the opposite ends of the cabinet as shown.

Legs 22 are pivoted to the outer extremities of the arms, and are capable of swinging downwardly to hold the outer ends of the arms spaced properly above the ground. The length of the legs is such that the arms 20 will be supported in horizontal position.

In practice, the cabinet, while removed from the vehicle running board, may be packed with cooking and serving utensils, a small stove, table cloth, napkins, and other necessary articles for preparing and serving meals. The cabinet may also be packed with articles of food. The door of the cabinet is then closed and locked, or turn buttons 24 may be employed to hold the door in closed position. The cabinet may be easily carried, and hand holds 25 may be secured upon the ends of the cabinet to facilitate lifting and carrying the same. When the cabinet has been placed upon the running board with the door disposed outwardly, straps 9 may be used to securely hold the cabinet in proper position. When it is desired to serve a meal the straps are detached and the arms 20 swung outwardly. The legs 22 are let down so as to support the extremities of the arms. The door may then be moved to open position, and the hinged leaves may be unfolded and laid upon the arms 20. Such of the utensils as are necessary in the preparation of the meal may then be removed, as well as the food stuffs. The seats of the vehicle may be removed from their proper places and positioned upon the ground around the table and will be found to be the proper height to accommodate persons eating from the table. After the table and articles are to be no longer used, the latter may be stored within the cabinet, and the leaf sections folded and swung with the door to closed position. The legs 22 are then swung upwardly and the arms 20 swung inwardly. The application of the straps 9 will then hold the cabinet to the running board and

will also prevent the arms 20 from protruding from the side of the vehicle.

It often happens that it becomes necessary to prepare and serve a meal after darkness and in such instances the cabinet may be wholly detached from the running board and placed upon the fender or guard at the front of the vehicle and in the path of light projected from the lamps of the vehicle.

From the foregoing, it is obvious that I have provided an extremely simple and yet thoroughly efficient means for attaining the various ends set forth, and one which will prove adequate for its purposes and highly practical in use.

While the present disclosure is that of what I believe to be the preferred embodiment of the invention, it is to be understood that the invention is not limited thereto, but that various changes may be made in the construction, arrangement, and proportion of parts, without departing from the spirit of the invention, as defined in the appended claims.

What is claimed is:—

1. In a device of the class described, a cabinet having a compartment at its bottom, a supporting arm pivoted at one end within said compartment and being capable of being housed by said compartment, a door hinged to said cabinet and being adapted to rest upon said arm when the latter is extended, and extensible leaves on said door.

2. In a device of the class described, a cabinet having a compartment at its bottom, a pair of supporting arms pivoted at their inner ends within said compartment and being capable of swinging within the latter, legs hinged to the outer ends of said arms, a door hinged to said cabinet adjacent the lower edge of the latter and being adapted to rest upon said arms, and leaves hinged to said door.

3. In combination with a motor vehicle; a cabinet adapted to be secured to the running board thereof, the said cabinet being divided into compartments, a pair of arms hinged at one end within one of said compartments and being capable of being swung outwardly therefrom, a door hinged to said cabinet, and extensible leaves on said door adapted to rest upon said arms.

In testimony whereof I affix my signature in presence of two witnesses.

ELMER McBURNEY.
